UNITED STATES PATENT OFFICE

115,308

DESIGN FOR A STOKER

Verdrie F. Clark, New Albany, Ind., assignor to
Peerless Manufacturing Corporation, Louis-
ville, Ky.

Application May 2, 1938, Serial No. 76,933

Term of patent 3½ years

To all whom it may concern:

Be it known that I, Verdrie F. Clark, a citizen
of the United States, residing at New Albany,
in the county of Floyd and State of Indiana, have
invented a new, original, and ornamental Design
for a Stoker, of which the following is a specifi-
cation, reference being had to the accompanying
drawing, forming a part thereof.

In the drawing:

Figure 1 is a perspective view of a stoker show-
ing my new design,

Figure 2 is a top plan view thereof.

The other side of the hopper portion is similar
in appearance to the side shown in Figure 1.

I claim:

The ornamental design for a stoker, as shown
and described.

VERDRIE F. CLARK.
